LOUIS MARIE GABRIEL DELAUNAY-BELLEVILLE, OF NEUILLY SUR SEINE,
FRANCE.

WATER-CIRCULATING APPARATUS.

No. 853,866.

Specification of Letters Patent.

Patented May 14, 1907.

Application filed December 4, 1905. Serial No. 290,223.

To all whom it may concern:

Be it known that I, LOUIS MARIE GABRIEL DELAUNAY-BELLEVILLE, engineer, a citizen of the French Republic, residing at Neuilly-sur-Seine, Department of the Seine, France, and having post-office address 17 Boulevard Richard Wallace, in the said city, have invented certain new and useful Improvements in Water-Circulating Apparatus, of which the following is a specification.

This invention has for its object to provide an improved apparatus for producing a circulation of water in the radiator of motor vehicles.

15 In the drawing: Figure 1 is a front elevation of an apparatus embodying the features of the invention. Fig. 2 is a transverse vertical section on the line 2—2, Fig. 1.

20 In order to demonstrate the advantages of the improved apparatus and its operation, a motor and circulation pump have been shown to the right of the radiator, but it will be understood that the motor and pump may be located in different positions with relation to the radiator.

25 The radiator tube A is shown as cylindrical in form, but may be varied in contour and is surrounded by a fixed reservoir B, the tube being completely closed and not in communication with the reservoir. Two chambers 1 and 2 are provided in the casing of the radiator A and have communication with the inner portions of the apparatus by means of pipes 3 and 4. A centrifugal pump C exerts 30 suction at the lower part of the reservoir B through a pipe 5 and forces water into the radiator through the pipe 3, as shown by Fig. 1. The radiator is provided with a series of baffles 6, arranged to extend only partially 35 across the radiator so that circulating spaces will be formed between the ends thereof and the adjacent portion of the casing of the radiator in alternation. The water from the pipe 3 enters the radiator below the lower baffle 6 and rises and traverses all the baffles, as indicated by the arrows in Fig. 1, and passes out 40 through the pipe 4 which is connected to the radiator at a point above the uppermost baffle, the pipe 4 connecting with the chambers of the motor D. The water passes out 45 through the upper portion of the motor D and is conveyed by a pipe 7 communicating with the upper part of the reservoir B, the water descending in this reservoir without 50

obstruction into the lower part of said reservoir, where it is again acted upon by the pump C. Connected to the upper part of the reservoir is an exhaust pipe 8 for liberating the steam from the water at the top of the reservoir. The radiator has a drain opening 55 9 formed in the lower portion thereof and provided with a cock or plug of ordinary form, this opening being used for emptying the radiator when desired. The reservoir B also has a lower opening 10, closed by a removable cock or plug for draining purposes.

The advantages of the apparatus specified are as follows: The water forced by the pump circulates more rapidly in the radiator than when gravity alone is relied upon, or is 60 more effective than where a suction pump is used for establishing a circulation. Owing to the circulation taking place from the lower portion upwardly through the radiator, said radiator is always filled with water, and all 65 the surfaces are completely covered. The accelerated and forced circulation of the water due to the connection of the parts hereinbefore noted, produces a more intimate contact of the water with the cooling tubes, 70 so that a greater reduction in the temperature of the water takes place. Furthermore, the friction of the water against the tubular surfaces being greater, any impurities contained in the water have less tendency to 75 adhere to the tubes and the cooling surfaces remain clean for a longer period. The water leaving the chambers of the motor at a considerable temperature may have liberated 80 earthy salts, and the water descending without any obstruction or obstacle to the bottom of the reservoir brings with it any salts 85 that it may contain, and which will be, to a large extent, deposited and freed from the water, the deposit of these salts taking place 90 in the bottom of the reservoir. This gravitation of the salts or other matter carried by the water, and the disposition thereof at the bottom of the reservoir preserves the cooling surfaces in a clean condition for a 95 longer period, and consequently the efficiency of the cooling surfaces is maintained for a longer time than if the water passed through the radiator as soon as it left the motor.

Having thus described the invention, what is claimed, is:

1. The combination with a motor for mo-

tor vehicles and a circulation pump, of a radiator, a reservoir, a tubular connection between the lower portion of the pump and the bottom of the reservoir, a connection between the upper part of the pump and the lower portion of the radiator, and tubular connections between the upper part of the motor and the radiator and reservoir respectively.

2. In an apparatus of the class specified, the combination with a motor and circulating pump, of a radiator having a series of baffles therein, a reservoir; and connections between the lower portions of the radiator and reservoir and the pump and between the upper por-

tions of the radiator and reservoir and the motor, whereby the water will circulate upwardly through the radiator and be fed to the motor and downwardly through the reservoir and be supplied to the radiator.

In testimony whereof I have hereunto set my hand in presence of two subscribing witnesses.

LOUIS MARIE GABRIEL
DELAUNAY-BELLEVILLE.
